UNITED STATES PATENT OFFICE.

WILLIAM T. MCCLURE, OF JOE, AND WALTER N. MITCHELL, OF BLUE RIDGE SPRINGS, VIRGINIA.

RAILROAD-GATE.

SPECIFICATION forming part of Letters Patent No. 267,705, dated November 21, 1882.

Application filed August 12, 1882. (No model.)

To all whom it may concern:

Be it known that we, WILLIAM T. MCCLURE, of Joe, in the county of Bedford, and WALTER N. MITCHELL, of Blue Ridge Springs, in the 5 county of Botetourt, and State of Virginia, have invented certain new and useful Improvements in Railroad-Gates; and we do hereby declare that the following is a full, clear, and exact description of the invention, which will 10 enable others skilled in the art to which it appertains to make and use the same, reference being had to the accompanying drawings, which form a part of this specification.

Figure 1 is a side view of our improved railroad-gate, showing also a transverse sectional view of the track; and Fig. 2 is a section on the line $\alpha\alpha$, Fig. 1.

Similar letters of reference indicate corresponding parts.

This invention relates to railroad-gates; and it consists in certain improvements in the construction of the same, which will be hereinafter fully described, and particularly pointed out in the claim.

A in the drawings represents a narrow pit, formed transversely in the road-bed, under and transverse to the track.

B are posts or uprights set in the sides or ends of said pit and extending some distance 30 above the track, so as to form guides for the gate C, which slides vertically between said posts B. The gate consists of a base or sill, D, a center panel, E, which slides or fits between the rails F F of the track, pickets G, 35 and vertical side or end posts, H. The latter are equipped with pulleys I on their outer sides, which work in grooves J, in order to cause the gate to work steady and to reduce friction to a minimum.

The posts B have pulleys P at their upper

ends, over which pass cords K, the inner ends of which are attached to hooks L at the upper ends of the gate-posts H. The outer ends of the cords K carry weights M, which serve to balance the gate. The posts H are provided 45 on their inner sides, near their upper ends, with brackets N, forming rests for the bars O, the ends of which are pivoted to the rails on both sides of and at some distance from the gate. The bars O may be pivoted either to 50 the inner or to the outer side of the rails, so as to be operated upon by the flange or tread, as the case may be, of the wheels of rolling-stock passing the gate.

The operation of this invention will be easily 55 seen. Pressure upon any of the bars O by the wheels of cars approaching the gate will force the latter down into the pit A, where it remains until the pressure upon the bars O ceases, when it is automatically returned by the balance- 60 weights M to its raised or closed position.

We claim and desire to secure by Letters Patent of the United States—

The herein-described railroad-gate, consisting of the sill D, center panel, E, composed of 65 pickets G and end posts, H, having brackets N, the whole adapted to slide vertically in a pit under the track between posts set in said pit, in combination with balance-weights and cords and the pivoted operating-bars O, as set 70 forth.

In testimony that we claim the foregoing as our own we have hereto affixed our signatures in presence of two witnesses.

WILLIAM THOMAS MCCLURE.
WALTER NAUGLE MITCHELL.
